(57) **CLAIM**

The ornamental design for a post press machine, as shown and described.

DESCRIPTION

FIG. 1 is a front, right perspective view of the post press machine;

FIG. 2 is a top side view thereof;

FIG. 3 is a left side view thereof;

FIG. 4 is a right side view thereof;

FIG. 5 is a front side view thereof; and,

FIG. 6 is a rear side view thereof.

The invention includes a plain and unornamented bottom, which is not shown.
